ROLLING MILL APPLIANCE

John A. Smitmans, Pittsburgh, Pa., assignor to
 United Engineering & Foundry Company,
 Pittsburgh, Pa., a corporation of Pennsylvania

Application July 11, 1935, Serial No. 30,831

5 Claims. (Cl. 80—56)

This invention relates to rolling mills and more particularly to an improvement in filler blocks or spacing elements of the type used in the windows of the roll housings beneath the lower roll chucks to determine the elevation of the pass-line of the mill.

Filler blocks of this character are used primarily to maintain the pass-line of the mill at a selected elevation, and are necessitated by the change in 10 the diameter of the mill rolls when they are resurfaced or replaced, as they frequently are.

In certain mills it is desirable and in some essential that the pass-line be maintained at all 15 times at a selected elevation, and this is especially true in continuous mills as well as in various other mills in which the stock-handling apparatus with which they are equipped is fixedly mounted. It has been the customary practice in the past to use separate filler blocks for this purpose and to 20 position them individually below the lower roll chucks in each of the housing windows. This has usually been done after the old set of rolls has been removed and before the new set is inserted, by an operator climbing down into the pit, in 25 which the mill is located, and placing them, one at a time, by hand in the housing windows. Because of the weight of such blocks, which is frequently quite considerable, and the inconveniences encountered in manipulating them in the mill pit, 30 the job of installing and replacing them in this way has been one which is very undesirable as it is both difficult and laborious and, in addition, consumes considerable time.

With this in mind, it is an object of this invention to provide a filler-block structure which can be placed as a unit in and removed from the windows of both of the roll housings at the same time and by the same operation.

Another object is to provide a unitary filler-block structure of this character which may be installed and replaced by the same apparatus that is used to change the mill rolls, and with which auxiliary filler plates of varying thickness may be used to accurately determine the elevation of the pass-line.

These and various other objects, as well as the various other novel features and advantages of the invention, will be apparent when the following detailed description is read in conjunction with the accompanying drawing, of which Fig. 1 is a sectional view of a mill having installed therein a filler block embodying the invention and showing in full and dotted lines the manner in which it is removed from the roll housings by means of a roll-changing hook;

Fig. 2 a plan view of the filler block shown in Fig. 1; Fig. 3 a view taken on the line III—III of Fig. 2; Fig. 4 an elevational view of the hook-engaging end of the filler-block frame; and Fig. 5 a similar view of the other end of the frame showing an auxiliary filler plate and how it is attached to the frame.

Referring in detail to the drawing, the numeral 1 designates a rolling mill which is mounted in the usual pit 2 with its pass-line 3 disposed at a convenient working level above the floor-line 4 which forms the top of the pit. As shown, the necks 5 of the rolls 6 of the mill are mounted in the usual chucks 7 and supported in the customary fashion in the windows of the roll 15 housings 8.

To adjust the pass-line of the mill to a selected level in accordance with this invention, when the diameters of the rolls are changed, a filler-block frame 9 is employed, being fitted as a 20 unit beneath the lower roll chucks 7. At one end of this frame, and preferably the end opposite the driving spindles 10, there is provided a neck-like projection 11 having an extremity 11a which is similar in shape to the end of the 25 mill rolls. This projection is adapted to extend beyond the face of the roll housing where it can be conveniently engaged by a roll hook 12 and lifted from and replaced in the roll housing in the same fashion as the rolls as shown in 30 full and dotted lines in Fig. 1. A roll hook of this character is customarily provided for installing and replacing the rolls, and comprises a hook-like frame having a socket 13 at its lower end which fits over the end of the wabbler 35 connection 5a at the end of a roll and suitable means 14 at the upper end for connecting it to a crane, not shown, that is used to move the hook to and from the mill.

As shown more particularly in Figs. 2 and 5, 40 the filler-block frame 9, which is made as an integral unit, comprises essentially a pair of transversely disposed block sections 15 which fit directly beneath the lower roll chucks 7, a center spacing section 16 which separates the 45 chuck-engaging block sections 15, and the neck 11 which projects beyond the face of the roll housing and is provided at its end with a portion 11a which may be engaged by the same hook that is used to engage the end of the roll. 50

In order to vary the thickness of the block sections 15 to thereby compensate for variations in the roll diameters and hence adjust the pass-line level of the rolls, auxiliary filler plates 17 are employed. These are mounted on the tops 55

of the block sections 15 when the frame is out of the mill and are provided in varying thicknesses, being selected as to thickness for each roll change in accordance with the diameters

5 of the rolls. In this particular embodiment of the invention, to hold these auxiliary filler plates in position, although other means may be used for such purposes, the filler-block sections 15 are each provided in the upper surface thereof 10 with a pair of spaced holes 18 and the auxiliary filler plates with cooperating pins 19 on their under sides which fit in these holes.

Another feature of the frame 9 is that it is provided on its under side, at the outer end of 15 the two filler-block sections 15, with downwardly projecting, outwardly tapered guides 21 which are adapted to engage the outer edges of the roll housing and guide the frame 9 into position when it is placed in the housing. In addition, as shown more particularly in Fig. 5, the frame 9 may be also provided at the ends of the filler-block sections 15 with downwardly projecting flanges 22 for holding the frame against lateral displacement in the housing 25 windows, if the latter are developed in the bottoms thereof, as illustrated by dotted lines in the drawing, to receive such flanges.

When using such a filler-block unit all that is necessary to do when the rolls are changed, 30 in so far as the filler blocks are concerned, is to connect the roll hook 12 to the end 11a of the filler-block frame after the rolls are out of the mill, as indicated in Fig. 1, lift the frame out of the mill and up over the mill floor where 35 the workmen can easily replace the auxiliary filler plates 17 with filler plates of the proper thickness to accommodate the new or resurfaced rolls which are to be placed in the mill, and then reposition such frame in the roll housing. 40

Among the advantages of the invention is the provision of a filler-block unit which can be readily removed and replaced in the roll housing by a simple mechanical operation without 45 necessitating a workman getting into the mill pit and with a minimum of effort and time, and, as will be readily appreciated, although the invention has been illustrated and described in connection with a 2-high mill, it may be used 50 with any type of mill.

According to the provisions of the patent statutes, I have explained the principle and construction of my invention, and have illustrated and described what I now consider to be 55 its best embodiment. However, I desire to have

It is understood that, within the scope of the appended claims, the invention may be practiced otherwise than as specifically illustrated and described.

I claim:

1. A filler-block unit for use in the roll housings of a rolling mill beneath the chucks for the lower roll which comprises an integral frame provided with spaced filler-block sections adapted to fit under the roll chucks in both housings, 10 and provided with means at one end for receiving a tool for lifting the unit from and manipulating it into position in the roll housings.

2. A filler-block unit for use in the roll housings of a rolling mill beneath the roll chucks which comprises a frame adapted to fit under the roll chucks in both housings and provided with a neck at one end which extends beyond the outer face of the housing, and adapted to 20 receive a roll-changing tool.

3. A filler-block unit for use in the roll housings of a rolling mill beneath the roll chucks comprising a unitary frame which fits beneath the roll chucks in both housings and which is equipped 25 with an end portion that projects beyond the face of one of the housings for receiving a tool for lifting the unit from and returning it to the housing, and detachable auxiliary filler plates for 30 engaging the roll chucks.

4. A filler-block unit for use in the roll housings of a rolling mill beneath the chucks for the lower roll which comprises an integral frame provided on its upper side with spaced detachable filler plates for engaging the roll chucks at the two ends of a roll, at one end with means for receiving a tool for inserting it in and lifting it from the roll housings, and on its under side with guide flanges to facilitate positioning it in 40 the roll housings.

5. A filler-block unit for use in the roll housings of a rolling mill beneath the chucks for the lower roll which comprises an integral frame consisting of spaced transversely disposed filler-block sections, a central section connecting said filler-block sections, a neck joined to one of said filler-block sections for receiving a tool for inserting the unit in and removing it from the roll housings, removable filler plates mounted on 45 the top of said filler-block sections and guides for engaging the roll housings on the lower side of said filler-block sections.

JOHN A. SMITMANS.
